UNITED STATES PATENT OFFICE.

LOUIS STROHACKER, OF FREEPORT, ILLINOIS, ASSIGNOR TO STRUCTO MANUFACTURING COMPANY, OF FREEPORT, ILLINOIS, A CORPORATION OF ILLINOIS.

LOOM.

Application filed May 15, 1922. Serial No. 560,908.

To all whom it may concern:

Be it known that I, LOUIS STROHACKER, a citizen of the United States, and a resident of Freeport, Stephenson County, and 5 State of Illinois, have invented certain new and useful Improvements in Looms, of which the following is declared to be a full, clear, and exact description.

This invention relates to looms and its 10 principal object is to provide improved harness actuating means, whereby the work of manipulating the harness may be greatly simplified. Another object is to provide individual heddle frame operating means, 15 each cooperating with the other in such manner, that when any heddle frame, or any combination of heddle frames, is raised, any other raised heddle frame, or any combination of raised heddle frames, will be 20 automatically lowered, thereby relieving the user of any mental or manual effort to perform this function.

With this end in view this invention consists in a loom, having harness or heddle 25 frames, actuating levers, one for each heddle frame, by which any frame may be raised and automatically operating means for temporarily retaining heddle frames in raised condition, said means co-acting with all of 30 the heddle frame levers to bring about the release of a raised heddle frame, or combination of heddle frames, whenever any other heddle frame is being raised, whereby the raised heddle frame, or frames, may automatically return to its, or their, normal or 35 lowered position. The invention further consists in the provision of a latch or dog co-acting with the heddle frame levers and arranged to automatically engage with any 40 lever, which is being depressed to raise its heddle frame, and thereby hold the lever in depressed condition and having other means coacting with the levers arranged to automatically disconnect the latch or dog 45 from any depressed lever whenever any other lever is depressed. The invention further consists in the several novel features hereinafter fully set forth and claimed.

The invention is clearly illustrated in the 50 accompanying drawings, in which;

Fig. 1 is a side elevation, partly broken out, of a loom embodying a simple form of the present invention. Fig. 1^a is a perspec-

tive view of a shuttle used in connection with the loom; Fig. 2 is a vertical cross section taken on line 2—2 of Fig. 1; Fig. 3 is a vertical section taken on line 3—3 of Fig. 1 and showing the working parts in a different position, and Fig. 4 is a horizontal section taken on line 4—4 of Fig. 2. 55 60

Referring to said drawings, which illustrate one embodiment of the invention, the reference character 10 designates the frame work of the loom, which, for convenience, may be constructed of light gauge strips of 65 metal suitably secured together to provide a frame work of rigid and substantial construction. Briefly, the frame work comprises a rectangular base portion 11, from which rise upright frames 12, 13, 14. The 70 upright frame 12 supports the warp beam 15, the frame 13 supports the harness, and the frame 14 supports the cloth beam 16. The warp beam 15 and cloth beam 16 may be journaled on rods 17 which extend 75 through the uprights of the frames 12, 14 respectively, and have wing nuts 18 upon their threaded ends which may be screwed up against said uprights to clamp the warp beam and cloth beam in place. Above the 80 warp beam and cloth beam are breast beams, 19, 20, which conveniently may be formed as a part of the frames 12, 13.

Between the cloth beam 16 and harness frame 13 is the reed or beater 21, which is 85 pivotally connected to and extends up from the base 11. The heddle frames 22, 23, 24, 25, are guided to move vertically between channel shaped uprights 26 of the harness frame 13 and support the heddles 27. Each 90 heddle frame has horizontal frame bars 28, 29, 30, connected by vertical frame bars 31 and the heddles 27 are secured upon and extend between the horizontal frame bars 29, 30, of the heddle frames. They are slidably mounted on said heddle frame bars 29, 30, and between their ends are formed with eyes 32 through which the warp threads *a* are threaded. It will be understood that the warp threads *a* extend from the warp beam 15 over the breast beam 19 thence through the eyes 32 of the heddles, through the reed 21, over the breast beam 20 and to the cloth beam 16, to which their ends are fastened. By raising any heddle frame a shed is formed, through which a 100 105

shuttle B, or shuttles carrying the weft thread b, or threads are passed in weaving the cloth or other woven article.

The mechanism for actuating the harness 5 will now be described. Fulcrumed upon upper horizontal cross members 40 of the harness frame 13, are heddle levers 33, 34, 35, 36, which are connected at one end, to the heddle frames, 22, 23, 24, 25, by links 10 37, the arm 38 of each heddle lever being connected to its associated heddle frame by a link which conveniently may comprise a piece of wire hooked into holes formed in the lever and horizontal bar 28 of the heddle 15 frame. A rod or shaft 39 secured in the horizontal cross pieces 40 of the harness frame, forms the support for the heddle levers, and washers 41 interposed between the levers space them apart: the upright 20 harness frame members 26 are slotted, and the handles 43 of the heddle levers project out through said slots in position to be readily manipulated.

It is obvious, from the above description, 25 that by depressing the handle ends of the levers, the heddle frames will be raised and that any one lever, or any combination of levers, may be depressed at one and the same time to raise a heddle frame or a combination of heddle frames.

Supported upon the harness frame 13 is a latch or dog 42, which is arranged to engage any lever when fully depressed, thereby holding its handle end in depressed position with 35 its arm 38 and heddle carried thereby in raised position and said latch is arranged to be disengaged from the depressed lever or levers whenever any other lever is subsequently depressed. In the form of the invention illustrated, the latch 42 is pivotally mounted on a rod or pin 43, which is secured in the ears 44^a of a bracket 44 that is secured to the harness frame members 26.

In the simple form of latch illustrated, it 45 comprises parallel spaced, vertically extending latch bars 42^a, (one for each lever) secured to horizontal top and bottom connecting bars 42^b, 42^c. On each latch bar is a shoulder 46, which is located in a position 50 on the latch to be engaged with the arm of its associated lever (when the latter is depressed) or with a projecting portion or pin 47 that is secured to and projects laterally from each lever. A coiled spring 48 secured 55 to the upper end of the latch 42 and to the harness frame 13, acts to yieldingly swing the latch into the path of travel taken by the pins 47. It is obvious from the above, that if any heddle lever is depressed until 60 its pin 47 reaches the shoulder 46, the spring 48 will swing the shoulder over the pin 47 and prevent the return of the depressed lever until the shoulder is moved out of engagement with the pin. It will be understood 65 that when the latch is thereafter

swung back far enough to disengage the shoulder from the pin, the weight of the heddle frame and heddles, carried thereby will raise the handle end of the heddle lever to its former position.

In order that any depressed lever may be automatically disengaged from the shoulder of its associated latch bar, all of the latch bars are provided with cam faces 49, there being a cam face located in advance of or 70 above each shoulder 46, and lying obliquely across the path of movement of the pin on the lever associated therewith. By reference to Fig. 3 of the drawings, it will be seen that when a lever 36 is being depressed, its pin 75 47 first engages the cam face 49 associated therewith, and rides along the same, thereby swinging the latch in the direction of the arrow x, far enough to free any other pin 47 from an associated shoulder 46, in case 80 any pin is engaged thereby. Between the lower end of the cam face 49 and shoulder 46, is a plane or neutral face 50 which, when the latch has reached the position seen in Fig. 3, is approximately concentric with 85 the pivot of the lever whereby the lever (which is being depressed) may be moved along the neutral face 50 without swinging the latch any further, and at the same time permitting the released lever to return to its 90 raised or normal position before the pin of the lever, which is being depressed, runs off the neutral face 50 and is encountered by the associated shoulder 46. At this instant the spring 48 swings the latch toward the pin 100 100 and engages the associated shoulder 46 with the pin, thereby holding the lever in depressed position when released by the finger of the user. When any other lever is subsequently depressed or any combination of levers is depressed, the lever or levers, which are held in depressed position, will be released from the latch, and permitted to return to normal position the weight of the heddle frames, connected to those levers, 110 serving to return the levers to their raised position.

The shuttle B is of the hand type and has the weft thread b, wound thereon, and in the operation of weaving the shuttle is shifted 115 back and forth through the shed, which is changed, each time the shuttle is passed therethrough, by manipulation the heddle levers in accordance with a predetermined sequence to produce the desired woven effect. The batten, or reed, is manipulated in the customary manner as is well known to those skilled in this art.

The loom above described is particularly adapted for use by unskilled persons, both 125 for amusement and for educational and practical purposes. It is a practical loom, of strong and substantial construction, yet light enough to be easily and readily handled and carried about. It may be placed on a table 130

or other support, and in its present form may be "knocked down" and packed in compact form for shipment or storage.

More or less variation of the exact details of construction is possible without departing from the spirit of this invention; I desire, therefore, not to limit myself to the exact form of the construction shown and described, but intend, in the following claims, 10 to point out all of the invention disclosed herein.

I claim as new and desire to secure by Letters Patent:

1. In a loom, harness actuating mechanism, comprising heddle levers, each connected at one end to a heddle frame, and a latch having lever engaging shoulders, one for each lever, adapted to temporarily hold its associated lever in depressed position, 15 there being co-operating lever releasing means between the levers and latch, whereby any depressed lever is disengaged from the latch when any raised lever is being moved to its depressed position.
2. In a loom, harness actuating mechanism, comprising heddle levers, each connected at one end to a heddle frame, and means for holding the levers in depressed position, said means and levers having lever 20 releasing elements co-operating with each other to release depressed levers when any raised lever is being moved to its depressed position.
3. In a loom, harness actuating mechanism, comprising heddle levers, each connected at one end to a heddle frame, means for holding one or more of the levers in depressed position, and automatic release mechanism operating when a raised lever is 25 being moved to its depressed position, to release depressed levers.
4. In a loom, harness actuating mechanism, comprising heddle levers, each connected at one end to a heddle frame, and a 30 combined lever holding and releasing latch, co-operating with all of said levers, whereby when any lever is being depressed, all other depressed levers are released.
5. In a loom, harness actuating mechanism, comprising heddle levers, each connected at one end to a heddle frame, a lever holding latch having means operating to hold any depressed lever in its depressed position, said latch having other means 35 co-operating with all raised levers to release

any depressed lever whenever any raised lever is being depressed.

6. In a loom, harness actuating mechanism, comprising heddle levers, each connected with a heddle frame, and a lever holding latch, having shoulders, one for each lever, arranged to hold an associated lever in depressed position, said latch having also cam faces, one for each lever, arranged to be engaged by a lever while it is being depressed, whereby the shoulders of the latch are disengaged from any depressed levers and the latter are permitted to return to normal position. 60

7. In a loom, harness actuating mechanism, comprising heddle levers, each connected with a heddle frame, and latch bars, one for each lever, each latch bar having a shoulder and a cam face, said latch bars being connected to move in unison, a shoulder 70 of each latch bar being arranged to engage an associated lever to hold the latter in depressed position, and the cam face of each latch bar being arranged to co-act with its associated lever to release depressed levers 75 from the shoulders of the latch bars.

8. In a loom, harness actuating mechanism, comprising heddle levers, each connected with a heddle frame and a spring actuated, lever holding latch, co-operating 80 with all of the levers, said latch having lever holding shoulders, and lever releasing cam faces associated with each lever. 85

9. In a loom, harness actuating mechanism, comprising heddle levers, each connecting with a heddle frame, and each having a laterally projecting lug, and a spring actuated lever holding latch co-operating 90 with all of the levers, said latch having lever holding shoulders co-acting with said lugs 95 on the levers and having also cam faces co-acting with said lugs to release depressed levers from said latch.

10. In a loom, harness actuating mechanism, comprising heddle levers, each connected with a heddle frame, having a laterally projecting lug, rigidly connected latch bars, one for each lever, each latch bar having a shoulder arranged to engage the lug of an associated lever, to thereby hold said lever 100 in depressed position, and having also a cam face lying across the path of movement of the lug of an associated lever. 105

LOUIS STROHACKER.
